DATA TERMINAL CONSOLE

Elmer J. Stoltz, Castro Valley, and William J. Wohltmann, Jr., Mountain View, Calif., assignors to The Singer Company, New York, N.Y.

Filed Dec. 1, 1969, Ser. No. 20,318

Term of patent 14 years

Int. Cl. D14—02

U.S. Cl. D26—5

FIG. 1

FIG. 2

FIG. 1 is a front and right side perspective view of a data terminal console showing our new design; and

FIG. 2 is a rear and right side perspective view thereof, the left side being a mirror image of the right side.

We claim:

The ornamental design for a data terminal console, as shown and described.
